UNITED STATES PATENT OFFICE.

FERDINAND PHILIPS, OF PHILADELPHIA, PENNSYLVANIA.

APPARATUS FOR FORMING CURVED AND FLANGED OR RIBBED METAL BARS.

SPECIFICATION forming part of Letters Patent No. 651,052, dated June 5, 1900.

Application filed June 29, 1899. Serial No. 722,235. (No model.)

To all whom it may concern:

Be it known that I, FERDINAND PHILIPS, a subject of the Emperor of Germany, residing in the city and county of Philadelphia, in the 5 State of Pennsylvania, have invented a certain new and useful Apparatus for Forming Curved and Flanged or Ribbed Metal Bars, of which the following is a true and exact description, reference being had to the accompanying drawings, which form a part thereof.

My invention relates to the construction of apparatus for forming curved metal plates with flanges or ribs extending parallel to the plane of curvature. Particularly my invention is designed for forming sheet-metal plates or bars of this character, although in its broader features it is applicable also to rolled sections; and the particular object I have in view is the formation of pulley-rim sections, 20 although my invention is applicable as well to the curving of flanged bars into other structural forms. In the formation of sheet-metal rims or structural forms I first bend or fold the sheet along parallel longitudinal lines 25 into a flanged or ribbed bar of the desired conformation, and having secured such a bar, either in this way or as a rolled section, my method of bending to the desired curvature, which method is new with me and forms the 30 subject-matter of my divisional application filed September 18, 1899, Serial No. 730,827, is to press it progressively onto the face of a convexly-curved matrix and in a direction parallel to the plane or planes of its ribs or 35 flanges, while at the same time I support the flange or flanges at and near the point where they are being bent against lateral distortion, thus insuring that the flange after curving shall lie substantially in the same plane 40 as in the straight bar and also insuring a uniform degree of upsetting, crimping, or extension in the ribs or flanges, the permanent form of which prevents any sensible tendency in the curved bar to resume its original form. 45 In my said method the bar is held upon the face of the matrix at or near one end of the portion to be curved and then progressively bent over the matrix, being always anchored to the matrix immediately in the rear of the 50 portion being bent, and in this way the bending proceeds by a succession of "differential bends," so to speak, by which the strains are

brought upon the bar, and particularly its ribs or flanges, very gradually, but with the immediate completion of the bending operation upon the portion, however small, acted upon, and thus the bar, treated by my method, has during the operation no partially-bent portion, the untreated bar merging immediately into the completely-curved bar. 55

The concave matrix which I prefer to employ is a roller with which coacts a bending-roller acting to force the bar down upon the face of the matrix-roller; but this and the other details of the mechanism forming the 60 subject-matter of this application will be best understood in connection with the drawings, in which they are illustrated, and in which—

Figure 1 is a side elevation of my new bending-machine designed to carry into effect my process. Fig. 2 is a side elevation of the machine from the opposite side. Fig. 3 is a front elevation of the machine. Fig. 4 is a plan view of the machine, taken on the section-line 44 of Fig. 3. Fig. 5 is a longitudinal central section through a matrix-roller, showing a clamping device for anchoring the bar to be treated. Fig. 6 is a side elevation of a portion of the matrix-roll, showing the clamping device of Fig. 5. Fig. 7 is a central longitudinal section through a matrix-roller which I prefer to employ and which may be called a "collapsing matrix." Fig. 8 is a transverse sectional elevation taken on the line 88 of Fig. 7. Fig. 85 9 is a detail view showing a modified form of clamping device. Figs. 10 to 14 are a series of views illustrating, progressively, bending operations performed upon a plate of sheet metal in the operation of converting it into a 90 flanged or ribbed bar. Figs. 15 and 16 are perspective views illustrating further operations performed upon the bar in order to complete it in the form which I prefer. Fig. 17 is a perspective view showing the bar of Fig. 95 16 after it has been curved in accordance with my method. Fig. 18 is a perspective view illustrating another form of sheet-metal ribbed or flanged bar curved in accordance with my invention. Fig. 19 is an end view of two flanged 100 bars abutted together so as to form a section somewhat similar to that shown in Fig. 16 and which may be curved together, if desired. Fig. 20 is a perspective view of a flanged or

ribbed bar similar to Fig. 16, showing a provision for anchoring it on the matrix-roller; and Fig. 21 is a sketch view showing a modification or reversal of the conformation of the 5 matrix and pressure rolls.

The method of bending a metal plate into the forms shown in Figs. 14 and 16 and by the steps indicated in Figs. 10 to 16 of the drawings is described in another application 10 for Letters Patent filed by me June 30, 1899, Serial No. 722,412, in which case is also described and claimed mechanism especially adapted for effecting the folding indicated in Figs. 12 and 13. In still another application 15 for Letters Patent filed June 29, 1899, Serial No. 722,236, I have described the structural form indicated in the section of Fig. 18 and my preferred method for making this form from sheet metal.

20 Referring now again to the drawings, A A indicate the supporting-framings of my machine; A', a horizontally-extending table slotted as indicated at a', and A² an upwardly-extending portion of the framing slotted as indicated at a², A³ being a plate secured across the top of the upright slotted portion, formed with a perforation a³ for the passage of the adjusting-screw.

A⁴ A⁴ are beveled edges of the standard A², 30 extending out on each side of the slot indicated at a².

B is a plate formed, as shown, with an inwardly-beveled groove, the edges of which are indicated at B' B² and which lap over the 35 beveled edges A⁴ above mentioned.

I have indicated at b a shim between the bevel, while at b² I have shown a taper-recess formed in the inner face of the plate B, in which fits the tapered head C of a bolt C', the 40 edge of the head fitting up against the adjacent bevel edge A⁴, and it will be obvious that by means of such bolts, either with or without shims (indicated at b,) a very close fit can be made between the bevels of the plate B and 45 those of the standard A².

B³ indicates lugs extending inward from the plate B and lying within the slot a² of the standard A². These lugs are perforated and carry in or between them a nut, a threaded 50 rod (indicated at I) screwing into the nut, said rod being supported by the hub I', and a hand-wheel I², resting on the plate A³. By turning this threaded rod the plate B can be raised or forced down to any position desired.

55 B⁴ is a rearward extension of the plate B. B⁵ and B⁶ are bearings or supports for a shaft or bar D D'.

b⁵ b⁶ are bearings for a shaft E E'.

What I have referred to as a "shaft" or 60 "bar" D D' has for its function merely to support the outer end E' of the shaft E. Its outwardly-projecting portion is preferably made tapering, as indicated at D', and it is connected with the outer end E' of the shaft E 65 by a plate or bar F², connecting a hub F, through which passes the end of the shaft D

D', and hub F', through which passes the end of the shaft E.

E² is a gear-wheel secured on the end of the shaft E, the pitch-line of which would be of 70 the same diameter as the bending-roller secured on the same shaft and to be hereinafter described.

G G' represent a shaft supported in bearings a a of the frame-standards A A, the outer 75 end G' extending beneath the end E' of the shaft E and being formed, as shown, with a slot g'.

G² is a gear-wheel fitting on the end of the shaft G and having a pitch-line corresponding with that of the matrix-roller secured on the same shaft. The gear-wheel G² is in operative engagement with a gear-wheel E², as 80 shown.

H is a slide movable in the slotted plate A' 85 and carrying a bearing II' for a shaft, to one end of which is secured a gear-wheel II², and to the other end of which is secured a pulley-wheel II³, through which pulley-wheel the machine is driven. The plate H is made adjustable, so as to accommodate the gear II² 90 to different sizes of gear-wheels G².

J, Figs. 2, 3, 4, 5, and 6, is a simple form of matrix-roller, a preferred, though more complicated form being indicated in Figs. 7 and 95 8. The roller J is secured on the shaft end G', as shown, and is formed with an annular central slot J', adapted to receive and fit quite closely a flange or rib of the bar to be bent. As shown, I have also formed the 100 roller J with corner edges J² J², against which the edge flanges of the bar to be bent should fit closely.

K is the bending-roller in connection with which the matrix-roller works and which in 105 the case of bars having edge flanges is provided with outwardly-extending annular end flanges K' K', which fit over the side flanges of the bar, being bent on the matrix-roller, and coact with the side edges J² to prevent 110 lateral distortion of these flanges.

In working with a roller-matrix it is desirable that the bar should be clamped at one end to the matrix-roller. This may conveniently be done by the device indicated in Figs. 115 5 and 6, lugs J³ being formed on the inside of the roller and supporting fulcrum-pins L L', upon which are pivoted levers L' L', the inner ends of which may be forced apart, as by means of a screw L², so that their outer ends, 120 preferably corrugated, as shown at L³, may be made to bite upon and hold fast the web or rib of the flange-plate.

It will be obvious that in using such a form 125 of matrix-roller as J a certain amount of difficulty will be encountered in removing the bent plate from the matrix. To overcome this particularly, I have devised and prefer to use a collapsible matrix-roller such as is indicated in Figs. 7 and 8. In this construction 130 two independent hubs M M are carried on the shaft G', from each of which extends

the arm-supporting plate M', supporting the divisional parts M² M² of the roll-center, these parts being formed, as shown, so that when clamped together they leave a space m², forming an annular groove around the roller.

M³ M³ are annular flanges projecting outward from the plates M².

m' indicates openings through the web-plate M', extending from one of the hubs, and M⁴ represents perforated projections on the plate M' of the hub M, lying to the left.

M⁵ M⁵ are perforated projections extending through the flanges M³.

M⁶ M⁶ indicate cavities formed in the inner faces of the roller-sections, in which are situated plates or blocks M²¹.

M⁷ M⁷, Fig. 7, are pins projecting from opposite sides of the sectional roller into the roller-cavity m².

m⁷, Fig. 9, indicates an alternative device consisting of serrated jaws.

M⁸ M⁸, &c., are springs secured on the hub-sections M M.

M⁹ (see Fig. 7) indicates one of the symmetrically-disposed shoulders projecting from the plates M' and coacting with levers to be hereinafter described.

M¹⁰ M¹⁰, &c., indicate screw-rods passing through the perforations M⁴, said rods being threaded at one end and provided with forked ears m¹⁰ at the other end, said ears projecting through the opening m', heretofore referred to, and serving to support pins M¹¹, upon which are pivoted bent levers M¹², a portion m¹² of which is adapted to fit against the projection M⁹, as shown in Fig. 7, while the free end of the lever is coupled by a link M¹³ with lugs m¹⁴ of a sliding block M¹⁴. The block M¹⁴ is circumferentially grooved, as indicated at M¹⁵, and in said groove fits an annular ring M¹⁶, having upwardly-projecting pins m¹⁶ on its opposite sides, which are coupled to arms N' of a lever N², pivoted at N upon any convenient support, such as an arm A^X, extending up from the floor or bed of the machine.

M¹⁷ M¹⁷ are adjustable roll-rims longitudinally movable on the annular extensions M³ of the sectional roll-center. These rim-sections are provided with downwardly-extending lugs, as indicated at M¹⁸, through which adjusting-screws M¹⁹ pass in position to come in contact with rods M²⁰, extending through the perforations M⁵. The springs M⁸ rest against the lugs M¹⁸ and tend to press them inward, as shown.

In the position of the sliding block M¹⁴ shown in Fig. 7 the parts of the matrix-roll are locked together in the position they occupy when in operation. The flange or ribbed bar has its central rib (indicated at O') extending into the slot between the parts of the sectional center and its rim-flanges (indicated at O³) extending over the corners of the rim-sections M¹⁷. The free end of the lever M¹² is forced up, so as to draw the right-hand section inward by pressure upon the

shoulders M⁹. In pressing the two centers together in this way the bolts M²⁰ are thrust outward against the adjusting-screws M¹⁹, which, being attached to the rim-sections M¹⁷, press them outward in opposite directions and to the desired degree, and it will be observed that what may be called a "toggle-joint" lock is formed between the free end of levers M¹² and the lugs m¹⁴ of the sliding block M¹⁴ by the links M¹³. When the bar has been bent upon the matrix-roller and it is desired to remove it, the block M¹⁴ is drawn outward, drawing in or down the free ends of the bent levers M¹², and thus relaxing the pressure holding the parts together, whereupon the springs M⁸ will act to draw the roll-centers apart, while at the same time they thrust the sectional rim portions together, thus eventually collapsing the roll and permitting the easy withdrawal of the completed work from it.

Referring particularly to Figs. 10 to 17, O indicates the flat plate or bar of sheet metal. It is first bent, as indicated in Fig. 11, at o' o' to form the flanges O' O', which are in the completed bar to form the central rib or web of the section. It is next bent, as indicated in Fig. 12, at o² o² to form the folds O² O², which are then pressed in, as indicated in Figs. 13 and 14, until the flanges O' are brought together. The folds O² are then brought up into contact with the flat surfaces O of the plate, as indicated in Fig. 15, leaving a beading where the folds o² are made, and by subsequent operation this beading (shown in Fig. 15) is converted into flanges O⁸, as shown in Fig. 16, and the bar is then ready to be bent upon my machine as described and shown in the drawings, or the beading may be pressed into the flange in the bending-machine.

In place of making a "two-ply" sheet-metal bar, as I may call the one above described, the bar may be formed from sheet metal as indicated in Fig. 18, a central fold forming the rib or central flange P', the metal being folded outward, as indicated at P² P², and then inward again, as indicated at P³. Pulley-rims can also be made from two pieces in my machine and by my method by abutting together flanges Q' of plates Q Q and then subjecting the two plates together to the bending operation I have above described.

In rolling a section curved as is indicated in Fig. 18 the central slot for the web-rim of the plate is formed in the presser-roller K, as indicated in Fig. 21, while the matrix-roller may conveniently carry the outwardly-extending end flanges, as shown in the same figure. The operation is precisely the same so far as affording support against lateral distortion is concerned.

Having now described my invention, what I claim as new, and desire to secure by Letters Patent, is—

1. A machine for progressively bending flanged or ribbed metal bars having a matrix-

- roller upon and about which the bar is bent and a bending-roller coacting with the matrix-roller to progressively bend the bar into the matrix as it passes between the rolls said 5 rollers being shaped to form grooves for the flanges of the bars between the walls of which said flanges are confined at the time they are bent about and whereby they are protected against lateral distortion.
- 10 2. A machine for progressively bending flanged T-shaped metal bars having a matrix-roller upon and about which the bar is bent, said roller being formed with a circumferential groove corresponding in position 15 and width with the web-flange of the bar and a bending-roller coacting with the matrix-roller to progressively bend the bar about the matrix as it passes between the rolls.
3. A machine for bending flanged T-shaped 20 metal bars having a matrix-roller over which the bar is bent said roller being formed with a circumferential groove corresponding in position and width with the web-flange of the bar and with straight side edges over which 25 the edge flanges of the T-bar project, and a bending-roller having outwardly-extending flanges adapted to extend beyond the edges of the matrix-roller and lie against the edge flanges of the T-bar, said bending-roller co- 30 acting with the matrix-roller to progressively bend the bar on the matrix as it passes between the rolls and to prevent lateral distortion of the edge flanges of the bar.
4. In a machine for bending T-shaped 35 metal bars, substantially as described, a matrix-roller having a two-part distensible center and two-part collapsible rim edges and means as described whereby the distention

of the center permits the collapse of the rim edges. 40

5. The collapsible matrix-roller having a two-part distensible center M^2 M^2 between the parts of which is formed the slot m^2 in combination with two rim edges M^{17} M^{17} , supported and laterally movable on flanges of the 45 center pieces, distending rods acted on by the closing together of the center parts M^2 and acting against the rim edges to distend them and means for moving the center pieces toward and away from each other. 50

6. The collapsible matrix-roller having a two-part distensible center M^2 , M^2 , between the parts of which is formed the slot m^2 in combination with two rim edges M^{17} , M^{17} , supported and laterally movable on flanges of the 55 center pieces, distending rods acted on by the closing together of the center parts M^2 and acting against the rim edges to distend them, springs acting against the rim edges to collapse them, and means for moving the center pieces toward and away from each other. 60

7. In a machine for bending flanged metal bars the combination of a fixed shaft G , G' , a relatively-adjustable shaft, E , E' , a matrix-roll upon and about which the bar is bent 65 and a bending-roll secured on said shafts said rollers being shaped to form grooves for the flanges of the bars between the walls of which said flanges are held against lateral distortion, and gearing connecting said shafts to 70 drive the rolls with the same peripheral speed.
